UNITED STATES PATENT OFFICE.

JOSEE JOHNSON, OF NEW YORK, ASSIGNOR TO HIMSELF, AND JOHN WARD, JR., OF BROOKLYN, NEW YORK.

IMPROVED IRONING-TABLE.

Specification forming part of Letters Patent No. 35,735, dated June 24, 1862.

To all whom it may concern:

Be it known that I, JOSEE JOHNSON, of New York, in the county and State of New York, have invented a certain new and useful Improvement in Ironing-Tables; and I do hereby declare that the following is a full and exact description of the same, reference being made to the accompanying drawings, in which—

Figure 1 is a side elevation. Fig. 2 is a plan from below; and Fig. 3 is an end view, the black lines in all the figures showing the table extended ready for use and the red lines representing it folded for stowage.

The nature of my invention consists in constructing an ironing table with a top in the form of a broad press board and with a central supporting-frame hinged thereto, open at that end beneath the narrow end of the top, and supported on three legs, two of which are capable of being folded into a line with the frame, or of being extended to support the table, the top being so hinged to the frame as to be folded over parallel therewith for stowage or turned up in a horizontal position for use.

My invention, when opened for use, presents a firm and stiff table for ironing purposes, one end being so supported as to allow the placing of skirts or other similar garments over it without the necessity of removing any support or disturbing the position of the table. When closed, it folds into a small compass and occupies very little room on the floor.

To enable others skilled in the art to make and use my invention, I will proceed to describe its construction and operation by the aid of the drawings.

A is the top of the table, made in the form represented. The central supporting-frame is composed of two longitudinal bars, B b, connected firmly together under the broad end of the top by the vertical braces C c, as represented.

To one side of B the table-top A is joined by the hinges D, so as to be capable of assuming the positions shown in black and red lines. The open end of B b is supported by a broad foot, E, slightly arched at the bottom to give

a firmer base. To the other end of B b two legs, F F, are hinged by the hinges G, as represented, so as to be capable of standing at right angles to B b, as shown in black lines, or in line therewith, as shown by the red lines.

H H are buttons to hold the legs F F extended.

The top A is proportioned as represented, and of such size that its narrow end may serve in lieu of a bosom-board, a portion nearer the broad end as a skirt-board, and the wide end as a general ironing-table.

The frame B b is strongly made and supports the narrow end of the top A very rigidly. The under side of B is beveled off, as shown, so as to allow of the ready slipping on of articles of clothing in ironing bosoms, skirts, &c., thus doing away with the necessity for and the inconvenience of a movable support for that end of the table.

When folded, my improved table forms a thin package, which will stand against the side of the room out of the way, or can be set aside in a closet or other convenient place, requiring but little room, and being readily and quickly expanded for use.

I do not claim the employment of the hinged legs F F and a hinged top adapted to fold against a single central frame, for such are shown in a patent granted to me February 5, 1861; but

What I do claim as my invention, and desire to secure by Letters Patent, is—

The construction and use of an ironing-table with a tapering top, A, and with a central frame, B b, open at one end, as shown by M, to allow the slipping on of skirts and the like, supported laterally by folding legs F F, which are capable of being folded into a line with the said frame, so as to form a novel table possessing the advantages herein set forth.

In testimony whereof I have hereunto set my hand in the presence of two subscribing witnesses.

JOSEE JOHNSON.
